UNITED STATES PATENT OFFICE.

WILLIAM J. STRAUSS, OF ALLENTOWN, PENNSYLVANIA.

SANITARY COMB.

Application filed January 18, 1926. Serial No. 82,141.

This invention relates to toilet articles, particularly to combs, and has for its object the provision of a novel comb equipped with cleaning means adapted to be moved along the teeth for the purpose of scraping off any accumulation of dandruff, loose hair and other matter which gathers or collects on the teeth of the comb as the result of use.

An important object is the provision of a comb of this character having spring means normally holding the cleaning elements up against the back of the comb so as to be out of the way, the spring means being enclosed so as not to catch in the hair or cause any annoyance or inconvenience.

An additional object is the provision of a device of this character which will be simple and inexpensive in manufacture, easy to use, positive in action, efficient and durable in service, and a general improvement in the art.

With the above and other objects and advantages in view, the invention consists in the details of construction and the arrangement and combination of parts to be herein-after more fully described and claimed, and illustrated in the accompanying drawings, in which:—

Figure 1 is a side elevation of the comb showing it in normal position in full lines and showing the movable element in its operative position in dotted lines.

Figure 2 is an enlarged detail section taken through one end portion.

Figure 3 is a detail section taken on the line 3—3 of Figure 2, and

Figure 4 is a view illustrating the flexibility of the cleaning member.

Referring more particularly to the drawings, the numeral 10 designates, generally, a comb having a back 11 from which extends a plurality of spaced teeth 12 in the usual manner. At the ends of the comb are tubular enlarged guide portions 13 slotted at opposite sides as shown at 14 and containing coil springs 15. The tooth ends of the enlargements or guides 13 are closed as indicated at 16 while the other ends are open throughout as indicated at 17 so as to permit insertion of the springs within these members. Furthermore, the closed ends 16 preferably have curved surfaces 18 against which the finger or thumb of the operator may be placed for a reason to be explained.

The cleaner comprises an elongated bar 19 which is provided with a plurality of

holes 20 located at spaced intervals so as to be slidably engaged upon the teeth 12 of the comb itself. At the ends of the cleaner bar 19 are reduced extensions 21 which pass through the slots 14 in the guide members 13 and which have their terminals preferably threaded as indicated at 22 for engagement thereon of knobs or other elements 23 which will not only operate to hold the device in place but which will also act as finger holds by means of which the operator may move the cleaner bar longitudinally of the teeth for cleaning off any accumulations thereon.

In the use of the device, it will of course be apparent that it is used in exactly the same manner as any other comb except that it has the advantage of being equipped with the cleaner bar. Assuming that dandruff, grease, loose hair or any other matter has accumulated on the teeth of the comb, it will be seen to effect cleaning it is merely necessary that the operator place his thumb against the curved surfaces 18 at the ends of the members 13 and grasp the balls or knobs 23 with the forefinger and consequently move the cleaner bar longitudinally of the teeth toward the ends thereof for scraping off any accumulations. When this is done it is of course apparent that the springs 15 will be compressed and when the pressure upon the knobs is relieved these springs will operate to return the cleaner bar to normal position against the back of the comb.

From the foregoing description and a study of the drawings, it will be apparent that I have thus provided a simply constructed, inexpensive and highly efficient device for the purpose specified, and one which will perform all the functions for which it is intended. It is believed that the construction, operation and advantages will be readily apparent to one skilled in the art without further explanation.

While I have shown and described the preferred embodiment of the invention, it should be understood that I reserve the right to make such changes in the form, construction and arrangement of parts as will not depart from the spirit of the invention or the scope of the subjoined claims.

Having thus described the invention, I claim:—

1. In combination, a comb including a back portion having a plurality of spaced teeth projecting therefrom and provided at its ends with tubular guide members having

2 slots in opposite sides thereof, and a cleaning bar having a plurality of openings therein slidably engaged upon the teeth, the bar having reduced end portions slidable through the slots in said guide members, and coil springs located within said guide members engaging against said cleaning bar.

2. In combination, a comb including a back portion having a plurality of spaced teeth projecting therefrom and provided at its ends with tubular guide members having slots in opposite sides thereof, cleaning bar having a plurality of openings therein slidably engaged upon the teeth, the bar having reduced end portions slidable through the slots in said guide members, and coil springs located within said guide members engaging

against said cleaning bar, knobs upon the projecting ends of said reduced end portions, 20 the ends of said tubular guide members at the back of the comb being open and the other ends being closed and having curved finger engaging surfaces.

3. In combination, a comb including a back portion having a plurality of spaced teeth projecting therefrom, and provided at its ends with guides, and a spring pressed cleaning bar apertured for engagement upon the teeth and provided at its ends with knobs projecting beyond the guides, said bar being normally urged toward the back of the comb by the springs.

In testimony whereof I affix my signature.

WILLIAM J. STRAUSS.
